UNITED STATES PATENT OFFICE.

KARL E. OSSIAN JANSSON, OF FLUSHING, NEW YORK, ASSIGNOR, BY MESNE ASSIGNMENTS, TO STANDARD PLUNGER ELEVATOR COMPANY, A CORPORATION OF MASSACHUSETTS.

AUTOMATIC STOP FOR ELEVATORS.

1,169,722.

Specification of Letters Patent. Patented Jan. 25, 1916.

Application filed June 1, 1909, Serial No. 499,503.

Renewed September 20, 1912. Serial No. 721,521.

To all whom it may concern:

Be it known that I, KARL E. OSSIAN JANSSON, a citizen of the United States, and a resident of Flushing, in the county of 5 Queens, in the city and State of New York, United States of America, have invented certain new and useful Improvements in Automatic Stops for Elevators, of which the following is a specification.

10 My invention relates to automatic stops for elevators, and its object is to improve upon devices of this character, and to provide a simple and efficient apparatus for bringing elevator-cars to rest at the ends 15 of their paths of travel.

I will describe my invention in the following specification and point out the novel features thereof in the appended claims.

Referring to the drawings, Figure 1 20 shows in side elevation a hydraulic elevator of the plunger type, with my invention applied thereto. Fig. 2 is a side elevation on a larger scale of one of the stationary cams. In Fig. 3 I have shown in sectional plan 25 view a preferred manner of supporting the cams. Fig. 4 is a sectional side elevation of an improved valve which I have invented, and Fig. 5 is a sectional end view of the same. In Fig. 6 another arrangement of 30 my invention is shown, and the modified form of valve in the latter figure is shown in section on a larger scale in Fig. 7.

Like characters of reference designate 35 corresponding parts in all of the figures.

10 designates an elevator-car which is arranged to run vertically upon stationary guides 11.

12 is a plunger affixed to the car and running down into a cylinder 13.

40 14 designates a pressure pipe from a suitable source of supply, and 15 is the exhaust pipe. 16 is the main controlling valve for the elevator by means of which either of these pipes may be connected with the cylinder 13 at will. 17 and 18 are pipe connections between this valve and the cylinder.

19 is the counterweight which is connected with the car in the usual manner.

20 designates an automatic stop-valve of 50 novel construction which is interposed in the pipe connections 17, 18 and is therefore a stationary mechanism. This valve is shown somewhat in detail in Fig. 4. It comprises a piston rod 21 upon which are 55 mounted pistons 22, 23 and 24 which are

fitted within a cylinder 30. A casing which surrounds this cylinder is constructed to form a chamber 25 below the cylinder and certain passages leading to the chamber 25 and to the ports in the cylinder. One of 60 these passages 26 leads from the pipe 17 to a port 31 in the cylinder, and to the chamber 25 through a passage 27.

28 is a passage connecting with the cylinder through port 32, and with chamber 25 65 through passage 29.

33 is a swinging controlling blade pivotally supported within the chamber 25 and provided with a pair of projecting arms 34 and 35. The lower end of this blade may 70 also be provided with an antifriction roller at 36.

37 is a check-valve in the passage 27, and 75 38 is a check-valve in the passage 29. The stems in these check-valves extend down into chamber 25 to the arms 34 and 35. The check-valve stems and arms are so proportioned and arranged that when the controlling blade 33 is in its vertical position neither of the check-valves can close. 80

39 is a locking member which, when the valve is open, will assume a position below the path of movement of the controlling blade 33 and its roller 36, but when raised will hold the controlling blade in different 85 desired positions in a manner which will be fully described hereinafter.

On the upper end of the piston rod 21 a sheave 40 is rotatably supported. A rope or cable 41, which is connected with the counterweight 19, is run down under this sheave and up to the car 10. The rope is run over a sheave 42 on the car and to a bell-crank lever 43 to one arm of which it is affixed at 44. The bell-crank lever is pivoted at 45 to 90 the car and is provided at 46 with an antifriction roller which projects from one side thereof. A weight 47 supported upon the piston rod 21 keeps the rope 41 taut and tends to hold the lever 43 over against stop 104 48, and to hold the pistons within the valve 20 in their lower position. At 49 a yoke is shown which connects locking member 39 with the piston rod 21.

50 designates an adjustable stationary 105 cam in the elevator-well in the path of movement of the roller 46. This cam is preferably constructed of a T-rail 51 as shown in Fig. 3, supported to the building by means of eye-bolts 52. Bolts such as 110

at 53 project through these eye-bolts and through the web of the rail at intervals, and are fastened to the structural steel 54 or other suitable portion of the building in which the elevator is installed by means of nuts 55. The cam 50 is shown at the upper end of the elevator-well. A similar cam 56 is placed in the lower portion of the well.

Before describing the other figures of the drawings I will point out the operation of the apparatus which has been above described. While the car is in the portion of its travel intermediate the cams 50 and 56, the weight 47 will hold the automatic stop-valve pistons in their lower position. The rope 41 is of sufficient length to allow these pistons to move down far enough to cause the piston 23 to be below the port 31, but the piston 24 can never move down over port 32. The space between these two pistons affords a clear passage between the pipes 17 and 18 so that water or other fluid may pass through valve 20 in either direction. When the flow is from the pipe 17 to the pipe 18, as is usual during the upward movement of the elevator, it is evident that the hydraulic pressure is greater in the passages 26 and 27 than in the passages 28 and 29. This difference in pressure will cause the controlling blade 33 to be swung over to the left as it is shown in Fig. 4. This will allow the check-valve 37 to be closed but will tend to open wider the check-valve 38. When the flow is in the other direction these conditions will be reversed and the blade 33 will be swung to the other side. As the car nears either end of its travel the valve 20 will be automatically closed. Let us assume that the car is running up. When it reaches the desired point, roller 46 will be brought into contact with the cam 50. The latter is inclined to the direction of travel of the car so that the continued upward movement of the car will cause the lever 43 to be pushed over. This will pull the rope 41 and, through the connections previously pointed out, will raise the piston rod 21 and its connected parts. The effect of this will be to close the passage between pipes 17 and 18, thus bringing the car to rest by shutting off its motive fluid. This action may be made to take place as rapidly or as slowly as desired, depending upon the degree of inclination of the cam 50. Some parts of this action may be made to take place more rapidly than others.

I have shown that while the elevator is running up the controlling blade 33 will be swung over to the left. The upward movement of the piston rod 21 will, through the yoke 49, push the locking member 39 upward against this controlling blade and will thereby hold it over. By this arrangement the elevator may be started down again after having been automatically stopped.

When the valve 16 has been manipulated to cause the water to run out of the cylinder 13 to the discharge 15, this water will take the following path through the automatic stop-valve 20. From pipe 18 it may go through passages 28 and 29, past check-valve 38, which is now held open positively, and through check-valve 37 which will automatically open and allow the water to pass through passages 27 and 26 to the pipe 17, and thence through valve 16 to the discharge. As soon as the elevator has run down a sufficient amount to allow the weight 47 to move the piston rod downward this movement will unlock the controlling blade 80 by depressing the locking member 39 below the path of movement of roller 36, and the controlling blade will then be free to swing over to the other side. When the car nears the lower limit of its travel, the roller 46 will come in contact with cam 56, and as the latter is inclined in the opposite direction to the inclination of cam 50, this will cause the lever 43 to be pushed over and to actuate the automatic stop-valve in the manner 90 above set forth.

The automatic stop-valve 20^A shown in Figs. 6 and 7 and the connections between it and the actuating lever 43^A on the car differ somewhat from those previously described. Within a cylinder 30^A are three pistons, as before, mounted upon a piston-rod 21^A. Below the cylinder a chamber 25^A is provided which communicates with passage 26^A which connects with the pipe 17, and with passage 28^A which connects with pipe 18. Check-valves 37^A and 38^A control the connections between the chamber 25^A and these passages. The stems of these check-valves project through the casing into the path of movement of the upper arm of a T-shaped lever 60. This lever is pivoted at 61 in a yoke 62 which extends around the valve and to which the piston-rod 21^A, the actuating-rope 41^A, and the weight 47^A are attached. The pivot passes through and is vertically guided by a slot 63 in a lug 64 which depends from the bottom of the valve casing. An antifriction roller 65 is placed at the lower end of the T-shaped lever 60. In this case the piston-rod of the main controlling valve 16 is designated by 66. It is carried out through the end of the valve and is connected with the lower arm of lever 60 by means of a connecting-rod 67, between which and the piston-rod 66 are placed a pair of compression springs 68 and 69. This valve operates to stop the elevator in substantially the same manner as that previously described. The control of its check-valves, however, is in this case performed in a somewhat different manner. When the main valve is moved to cause the elevator to run up, its piston-rod 66 will be moved over to the left as shown in the drawings. 130

Through its connection with the lever 60 it will cause the latter to be tilted in the manner shown. When in this position the check-valve 37^A will be able to seat itself, but the other check-valve 38^A will be raised from its seat. Now, if the yoke 62 is raised to actuate the stop-valve, it will carry with it the T-shaped lever 60 which will tend to raise the check-valve 38^A higher. When this yoke and lever are raised, the roller 65 will pass to one side of the lower pointed end of the lug 64, and this will cause the lever to remain in its tilted position after the piston-rod 66 has been returned to its central position, and even after it has been moved over to the right as far as it will go. The resilient connection between the piston-rod and the lever 60 provides for this movement. It is evident now that when the main valve 16 is moved over to cause the elevator-car to run down, that the water will pass from the cylinder 13 through pipe 18, passage 28^A; past check-valve 38^A which is locked in its open position in the manner which is described; through chambers 26^A and 26^A to the pipe 17. This automatic stop-valve has its pistons held, as in the previous case, in their lower position by a weight 47^A which is affixed to the yoke 62. To the upper end of this yoke a rope 41^A is attached which is run up through the elevator-well and fastened to the upper end thereof as at 41^B. The lever 43^A is pivoted as before at 45, but in this case is connected with a cross-arm 35 upon the ends of which are carried pulleys 44^A and 44^B which engage with and run upon opposite sides of the rope 41^A. In this case when the lever 43^A is pushed over by one of the cams it will swing these pulleys in opposite directions and thereby take up the rope 41^A and raise the yoke 62 with its connected parts to thereby operate the valve 20^A. By these simple arrangements the troublesome deflecting ropes or movable cams which have heretofore been used to actuate automatic stop-valves are dispensed with.

It will be observed in the construction herein described, that the valve is moved by a longitudinal pull on the vertical sided loop of rope having its ends connected to run with the car, and one of said end connections including a movable take up device actuated by stationary means outside the car. By this construction, the actuating pull which can be applied to the valve will depend upon the strength of the rope, and such pull will directly and positively move the valve to effect a safe stop of the car. It will also be seen that a single running rope connected to a single valve having an open and a closed position effects a positive closing of the valve at each end of the run, when the take up device is actuated, the weight 65 simply serving to open the valve and restore

the take up device to its position for the next stop. The position of the cams is adjustable and may easily be set to suit conditions or changed at will to obtain different desired actions of the stop-valve. A gradual slow-down with a quicker stop may be obtained, or, in the same installation, the cam may be adjusted to cause a quicker-acting slow-down with a more gradual final stop. 75

A single automatic valve such as herein disclosed is arranged to do the work for which two valves are usually required. This valve has been made the subject-matter of another application for patent which is filed herewith and given Serial Number 499,504. This one valve, as has been shown, will stop the flow of fluid in either direction and still allow the fluid to flow in the direction opposite to that in which its flow has been 85 stopped.

I have shown this invention applied to a hydraulic elevator as it is especially adaptable to elevators of this class. But I do not limit its use to hydraulic elevators as automatic stop devices embodying the novel features of this invention may be designed for other types of elevators. I have illustrated more than one arrangement of the actuating mechanism and more than one 95 design of valve to show that I do not limit myself to any specific arrangements or constructions.

What I claim is:—

1. An elevator-car, an automatic stop device therefor, an automatically actuated lever on the car for actuating the stop device, stationary cams near the ends of travel of the car, both of said cams being arranged to cause the movement of the car to actuate 105 the lever in one direction to stop the movement of the car in one direction or the other, and a rope between said stop device and the actuating lever.

2. An elevator-car, an automatic stop device therefor, a lever on the car for actuating the stop device, stationary cams near the ends of travel of the car for causing the movement of the car to actuate the lever, adjustable supports for the cams, and a rope 115 arranged to run with the car, connecting said stop device and the actuating lever.

3. An elevator-car, a hydraulic hoisting mechanism, an automatic stop-valve therefor, means for holding said valve open, a 120 lever on the car for moving the stop-valve into closed position, stationary cams near the ends of travel of the car for causing the movement of the car to actuate the lever in one direction, and a rope between the stop-valve and the actuating lever to close the valve against the action of said holding means.

4. An elevator-car, a hydraulic hoisting mechanism, an automatic stop-valve there- 130

for, a lever on the car for moving the stop valve in one direction to close said valve, stationary cams near the ends of travel of the car for causing the movement of the car 5 to actuate the lever, adjustable supports for the cams, a rope between the stop-valve and the actuating lever, and a weight arranged to hold the lever over and the valve open when the latter is not acted upon by said 10 cams.

5. An elevator-car, a hydraulic hoisting mechanism, a controlling valve and an automatic stop-valve therefor, stationary cams near the ends of travel of the car, means 15 operating therewith actuated by the movement of the car in either direction for moving the stop-valve in one direction, to thereby stop the car, and said stop-valve comprising means dependent upon the position of 20 the controlling valve when the stop-valve is actuated for allowing the car to be started in the opposite direction.

6. An elevator-car, a hydraulic hoisting mechanism, a controlling valve and an automatic stop-valve therefor, means on the car for actuating said stop-valve, stationary cams near the ends of travel of the car for causing the movement of the car in either direction to move said actuating means in 25 one direction, a flexible connection between the stop-valve and the actuating means on the car for causing the movement of the actuating means to close the stop-valve; said stop-valve comprising means dependent upon the direction of movement of the car at 30 the time the stop-valve is closed for allowing the car to be started in the opposite direction.

7. An elevator-car, a mechanism controlled by the flow of a fluid in one direction or the other for causing the car to run up or down, a controlling valve and an automatic stop-valve for said fluid, a lever on the car for actuating said stop-valve, stationary cams near the ends of travel of the car for causing the movement of the car 40 in either direction to move said lever in one direction, a rope between the stop-valve and the lever for causing the movement of the lever to close the stop-valve to thereby stop the flow of fluid and the movement of the car, and means for holding the stop-valve open when not acted upon by said actuating 45

means; said stop-valve comprising means dependent upon the direction of flow of the fluid at the time the stop-valve is closed for 55 providing a path for the flow of the fluid in the opposite direction.

8. An elevator-car, an automatic stop device therefor, and means connecting the car and said device arranged to be actuated by 60 the movement of the car in either direction for moving a part of said stop device in one direction to thereby stop the car, said stop device comprising means automatically set by the direction of flow of 65 the motive fluid at the time said stop device is actuated to stop the car and controlled by the actuation of the stop device, for allowing the car to be again started in the opposite direction. 70

9. An elevator car, a hydraulic hoisting mechanism, an automatic stop device therefor, means actuated by the movement of the car in either direction for moving a part of the stop device in one direction to thereby stop the movement of the car in either direction, said stop device comprising a bypass, controlling means in said bypass for allowing fluid to flow therethrough in one direction or the other, and intermediate connections between said movable part of the stop device and the controlling means in said bypass whereby said controlling means is controlled. 75 80

10. An elevator car, an automatic stop mechanism therefor, and means connecting the car and said mechanism arranged to be actuated by the movement of the car in either direction for moving a part of said stop mechanism in one direction to thereby automatically stop the car; said mechanism containing means for permitting the car to be started in a direction opposite to that in which it was moving before being automatically stopped, and a device actuated by the 90 movement of said part of the stop mechanism for controlling said means contained in the mechanism. 95

In testimony whereof I have signed my name to this specification in the presence of 100 two subscribing witnesses.

KARL E. OSSIAN JANSSON.
